Inventor:

George Decker,
by John Elias Jones,
attorney.

UNITED STATES PATENT OFFICE.

GEORGE DECKER, OF CINCINNATI, OHIO.

MEN'S TROUSERS-SUPPORTER AND THE LIKE.

1,305,073.

Specification of Letters Patent. Patented May 27, 1919.

Application filed September 4, 1917. Serial No. 189,643.

To all whom it may concern:

Be it known that I, GEORGE DECKER, a citizen of the United States of America, and a resident of Cincinnati, in the county of 5 Hamilton and State of Ohio, have invented a certain new and useful Improvement in Men's Trouser-Supporters and the like, of which the following is a specification.

This invention relates to devices used instead of the ordinary suspenders to support 10 men's trousers and the like when in use, and the object of the invention is to provide a simple and convenient cast-off and button-engaging device that is removably attached 15 at its upper end to the shirt of the wearer and similarly attached at its lower end to the wearer's trousers, whereby two functions are performed at the same time, one being the more important one of supporting the 20 trousers and the other being that of holding the shirt down and preventing its rising from tucked place within the trousers.

The details of structure will be fully hereinafter described and then particularly 25 pointed out in the claim that follows.

In the accompanying sheet of drawings:—

Figure 1 is a front elevation of the device as it appears in use, showing fragments of 30 the waist-portion of the trousers and body-portion of the adjacent shirt;

Fig. 2, a vertical section taken on the dotted-line α , α , of Fig. 1, but omitting the fragment of the shirt;

Fig. 3, a rear elevation of the device it- 35 self;

Fig. 4, a perspective view of the device with the fastening-loop of its cast-off member swung forward in open position ready for application to the shirt: and—

Fig. 5, a front elevation of a modification, showing my device with a bifurcated pair of elastic buttoning-ends instead of the single elastic buttoning-end seen in each of the previous views.

Fig. 1 indicates a vertical elastic strip forming the body-portion of my device, having at its lower end a button-hole 2.

This elastic strip is preferably made double, being folded as shown at 3 at its 40 lower end, whereby it has the desired strength and resiliency, as well as endurance to accomplish the object hereinbefore named.

Fig. 4 indicates a vertical inelastic strip of tape or other suitable, pliable fabric folded at its lower end so as to embrace the upper 45 end of the double elastic strip 1 to which

it is stitched or otherwise securely attached. This strip 4 is also double and folded so as to provide a loop 5 at its top and a loop 6 near its lower end, said loop 5 accommo- 60 dating the wire backing 7 of a forwardly-projecting stud or button 8, and the loop 6 accommodating the lower horizontal bar 9 of the wire fastening-loop 10 of a cast-off member that swings from said loop 6 65 and has a contracted upper end 11 for interlocking-engagement, as customary in cast-off devices of this type, with the stud or button 8. The stud 8 is preferably covered or faced with a padding of rubber, as best 70 shown in Fig. 2, so as to make better frictional contact with the shirt goods and without damage to the latter in use.

A indicates a fragment of the upper waist-portion of the trousers, and B a fragment 75 of the body of the shirt. The right and left side portions of the trousers and shirt are the ones in connection with which my device is preferably used, so that but two of the devices need be used in order to equalize 80 the suspension of the trousers from the buttons 12 on the inner face of the waist-band at the right and left sides of the person and using the weight of the trousers to simultaneously pull or draw downwardly on the 85 shirt to prevent its undue rising above the waist-band of the trousers, and thereby impart a neat appearance to the shirt as well as to avoid the necessity of too frequently and unsightly tucking the shirt down into 90 place within the trousers.

The customary belt C may be worn to aid, if desired, in supporting the trousers, especially when the pockets thereof are more or less filled with heavy articles that would 95 exert undue weight on the cast-off connection with the shirt and otherwise cause it to rupture or tear.

In Fig. 5 is shown a modified form in 100 which a pair of elastic ends or strips 1^a, 1^a, extends in fork-form from the lower end of the inelastic strip 4, the latter having the same cast-off devices for connection with the shirt, as disclosed in the other views. The outer ends of said strips 1^a, 1^a, are provided with button-holes 2^a, 2^a, for connection with buttons on the inner face of the waist-band, such buttons being preferably arranged at either side the center of the left 105 and right sides of the trousers for the desired uniform suspension of the garment on the person.

In Fig. 1 is shown how the shirt goods is folded and gathered at 13 to surround the stud 8 and interlocked in place by the engagement of the contracted portion 11 of the 5 cast-off member 10 with the shank of said stud.

I claim:—

In a device for detachably supporting men's trousers and the like from the wearer's shirt or other upper garment, the combination of a vertical elastic strip or body-portion having a button-hole at its lower end, a single inelastic tape extending vertically from the upper end of said elastic 10 body-portion and having a forwardly-projecting stud at its upper end, and a swing-

ing cast-off loop having a horizontal bar at its lower end adapted to have pivotal-engagement with a loop in the lower end of said inelastic tape and, also, having its upper end contracted for interlocking-engagement with the said stud when the latter has a fold or gathering of the shirt goods surrounding it, the button-hole end of said elastic body-portion being adapted for engagement with a button on the trousers waist-band for elastically supporting the trousers from the shirt or other upper garment and simultaneously preventing the latter from unduly rising on the person while 15 20 25 30 in use, substantially as shown and described.

GEORGE DECKER.
